UNITED STATES PATENT OFFICE.

LEON DION, OF WILKES-BARRE, PENNSYLVANIA, ASSIGNOR TO THE AMERICUS ELECTRO-
HERMETIC COMPANY, OF WILKES-BARRE, PENNSYLVANIA.

ELECTRIC FURNACE.

No. 888,877.

Specification of Letters Patent.

Patented May 26, 1908.

Application filed April 30, 1906. Serial No. 314,337.

To all whom it may concern:

Be it known that I, LÉON DION, a citizen of the United States, residing at Wilkes-Barre, in the county of Luzerne and State of Pennsylvania, have invented certain new and useful Improvements in Electric Furnaces, of which the following is a specification.

My invention, while relating to electric furnaces generally, has reference more particularly to that class of such devices which are employed in the fusing of metals when in both their crude and in their reduced states; its object being to produce a furnace of this character, which, while simplified in construction and rendered more efficient in operation than those heretofore in use, shall, at the same time, permit of the fusing of the metal without the escape and loss of the fumes and vapors arising therefrom.

To these ends, the invention consists in certain peculiarities of construction and arrangement of parts, the form of which I prefer to use in practice being shown in the accompanying drawing, in which

Figure 1, is a longitudinal vertical central section of a furnace constructed in accordance with my invention, and Fig. 2, a horizontal transverse section thereof taken in the line $z-z$ of Fig. 1.

In both figures the same letters of reference are employed to designate corresponding parts.

A indicates an inclosing structure, which may be constructed of brick or other heat resisting material, and B indicates a bowl or crucible in which the heating and fusing of the metal or ore is effected.

In the construction of the inclosing structure A, various means may be adopted. In the drawings however, it is constructed as of a general rectangular form in horizontal cross-section, and as provided in its interior with a chamber a, to which access may be had through a suitable opening or door a^1 , formed in the top of the structure over the chamber and which may be closed when desired by a suitable cover a^2 . Within the chamber a as thus provided is centrally arranged the bowl or crucible B, which, as with the inclosing structure A, may be constructed of any appropriate form and material that will suit it to its intended use. In the form of the invention which I have selected for purposes of illustration however,

this bowl or crucible is shown as constructed of a rectangular form in horizontal cross-section, with an upper enlarged portion b, and a lower reduced chamber portion b^1 , that is or may be provided with a downwardly and laterally extended tubular portion b^2 , which, in practice, preferably extends downwardly and outwardly through the side of the inclosing structure A and may be closed by a suitable plug b^3 inserted in its lower outer end.

With the bowl or crucible B constructed and arranged as thus explained, it receives near the lower end of its enlarged portion b, the electrodes c and c^1 , which extend inwardly and downwardly toward each other through the walls of the inclosing structure and through the walls of the bowl or crucible in a downwardly and inwardly inclined direction, with their inner ends in close relationship to each other, but slightly separated. In these positions the electrodes may be supported by any appropriate means. I prefer however, to support them in those positions by suitable holders c^2 and c^3 , which are or may be secured to the inclosing structure A, from which they are or may be insulated by insulating strips c, and are severally provided with suitable holding guide-ways c^4 and c^5 , through which pass the respective electrodes, with the positive or + member, and the negative or - member, respectively connected to the positive and negative poles of a dynamo or other source of electric supply, through suitable conductors c^6 and c^7 with which the electrodes are respectively provided. The electrodes c and c^1 being thus arranged, the metal or other material to be treated may be supplied to the bowl or crucible from any appropriate source. I prefer however, to supply it thereto through a hopper C, which is supported upon the top of the inclosing structure A and is connected with the bowl or crucible through a chute-way a^3 , formed in the inclosing structure and extending from the bottom of the hopper C to the upper end of the bowl or crucible, and rendered capable of being closed when desired by a suitable door or slide a^4 , which may be passed downward through the walls of the inclosing chamber across the chute-way, as shown in Fig. 1.

With the hopper and chute-way thus arranged, the metal or other material to be treated will be deposited in the hopper C,

whence it will pass downward through the bottom of the latter and through the chute-way a^3 to the bowl or receptacle B, and thence to and upon the electrodes c and c' , 5 upon the inner ends of which it will rest and its fusing take place when the electrodes are supplied with the appropriate electric current. The material thus fused will then pass downward between the electrodes to 10 the lower contracted chamber portion b^1 , from which it may be drawn through the tubular passage-way b^2 , by removing the plug b^3 from its lower end. In being thus subjected to the action of the electric current upon and between the electrodes and in 15 being fused thereby, more or less of the metal or other material in the form of fumes or vapor will arise therefrom; and, in order to accumulate and conduct them to appropriate concentrating and recovering 20 appliances, I provide the interior of the inclosing structure with an upwardly and laterally extending passage-way a^5 leading upwardly and outwardly from the chamber 25 a , and through which these fumes or vapors may pass, being accelerated in their movements and drawn upward therethrough when required by a blast of air supplied 30 through a pipe a^6 connected with an appropriate source of air supplied and leading downwardly into and along within the passage-way a^5 , as shown in Fig. 1.

In the construction of the electrodes c and c' various forms may be adopted. I prefer however to construct them in the form of 35 plates and to provide the upper surface of each with a longitudinally extending shallow circular groove c^8 , whereby to conduct the molten material inward toward their longitudinal median line, or towards the point where the heat is the greatest.

With some kinds of metals and materials 40 the operation of the furnace may be continuous, and the metals or other materials supplied to the hopper C passed downward continuously through the chute-way a^3 to the bowl or crucible B where it is subjected to the action of the electric current passing through the electrodes, and in such cases the door or 45 slide a^4 will be opened or raised from the chute-way. With other kinds of materials on the other hand, as, for instance, the more valuable ones, when it is desired to recover the fumes or vapors arising from their fusion, 50 then, instead of the metal or materials being supplied to the bowl or crucible B continuously, they will be supplied thereto in measured quantities, and the door or slide a^4 , in those cases, will be opened only for sufficient 55 length of time to allow the required amount of metals or materials to be passed downward through the chute-way, when it will be closed and remain in that condition until a further quantity is to be supplied, to the end 60 that none of the fumes or vapors arising from

the fusion of the metal or other materials may be passed off through the chute-way and thereby lost.

In most cases the metals or materials being treated, when supplied to the bowl or crucible, will pass downward into the same and rest upon the electrodes c and c' at any point thereon within it. With others of a more refractory character, on the other hand, it will be found desirable to deflect the metals or materials thus supplied to the bowl or crucible inward toward the point of nearest approach of the electrodes to each other or to the point where the highest degree of heat is to be found. In such cases therefore I find it desirable to provide the interior of the bowl or crucible, a short distance above the electrodes, with a downwardly and inwardly inclined flange b^4 which extends around its interior, and to form beneath its underside through the walls of the bowl or crucible a number of holes or orifices b^5 , through which the fumes or vapors arising from the fusion may pass and be thence conducted through the chamber a to the passage-way a^5 for delivery to the accumulating and recovering devices, not shown.

With the parts constructed and arranged as above explained it will be seen that I provide an electric furnace, which, is not only simple in construction and capable of easy and efficient operation, but one in which the fumes and vapors arising from the fusion may be collected and delivered to the concentrating or other recovering devices without substantial loss.

While in the drawings I have shown, and in the foregoing described, the best means contemplated by me for carrying my invention into practice, I wish it distinctly understood that I do not restrict myself to the exact form of construction shown and described, as it is obvious that I may modify the same in various ways without departing from the spirit of the invention.

Having now described my invention and specified certain of the ways in which it may be carried into effect, I claim and desire to secure by Letters Patent of the United States,—

1. The combination in an electric furnace, with an inclosing structure provided in its interior with a chamber, of a bowl or crucible for receiving the material to be treated arranged in such chamber and provided with a contracted lower chamber portion to receive the metal or other material when fused, and electrodes, adapted to be connected with a source of electric supply, arranged to project into said bowl or crucible and across the path of travel of the material being treated as such material passes downward through the bowl or crucible, substantially as described.

2. The combination in an electric furnace,

with an inclosing structure provided in its interior with a chamber, a chute-way, and with a discharge passage-way, and a bowl or crucible for receiving the material to be treated arranged in said chamber and constructed with means by which its contents when fused may be discharged, of a hopper for receiving the metal or other materials to be treated connected with such bowl or crucible through the chute-way, and electrodes, adapted to be connected with a source of electric supply, arranged to enter the said bowl or crucible and extend inward across the path of travel of the material being treated as such material passes downward through the bowl or crucible, substantially as described.

3. The combination in an electric furnace, with an inclosing structure provided in its interior with a chamber and constructed with a chute-way and a discharge passage-way through which the fumes or vapors arising from the fusing of the material supplied through the chute way may pass, of a hopper through which the metals or other materials may be supplied to the bowl or receptacle through the chute-way, a door or slide for opening and closing such passage-way, and electrodes, adapted to be connected with a source of electric supply, entering such bowl or receptacle and extending inward across the path of travel of the metals or materials being treated as such materials pass downward through the bowl or crucible, substantially as described.

4. The combination in an electric furnace, with an inclosing structure provided in its interior with a chamber, of a bowl or crucible arranged in such chamber and constructed with both an inwardly and downwardly extending flange around its interior and with orifices formed through its walls beneath said flange, and means through which the metal or other materials to be treated may be supplied to such bowl or crucible, of electrodes arranged beneath said flange to receive and fuse such metal or materials, and means through which the supply of the metals or materials to the bowl or receptacle may be controlled, substantially as described.

5. The combination in an electric furnace, with an inclosing structure provided in its interior with a chamber, a chute-way and with a discharging passage-way, a bowl or crucible arranged in such chamber and constructed with both an inwardly and down-

wardly extending flange, a lower contracted chamber portion and with orifices formed through its walls beneath the inwardly and downwardly extending flange, of a hopper through which the metals or other materials to be treated may be supplied to the bowl or crucible through such said chute-way, means by which the chute-way may be opened and closed, and electrodes arranged beneath the inwardly and downwardly extending flange to receive and fuse the metals or materials supplied to such bowl or crucible, substantially as described.

6. The combination in an electric furnace, with an inclosing structure provided in its interior with a chamber, a chute-way and a discharging passage-way, of a bowl or crucible arranged in such chamber and constructed with both an enlarged upper portion that is equipped with an inwardly and downwardly inclined flange, a lower contracted chamber portion and a downwardly and laterally extending tubular portion leading from such contracted chamber portion to the exterior of the inclosing structure, electrodes entering such bowl or receptacle near the upper end of its lower contracted chamber portion and adapted to be connected with a source of electric supply, and means by which the metal or other material to be treated may be supplied to the bowl or receptacle through the passage-way and such chute-way opened and closed, substantially as described.

7. The combination in an electric furnace, with an inclosing structure provided in its interior with a chamber a discharging passage-way leading therefrom through which the fumes or vapors arising from the fusing of the materials within the inclosing structure may pass, a bowl or crucible arranged in such chamber, and means by which the metals or other materials to be treated may be supplied to such bowl or crucible, of electrodes entering said bowl or crucible and adapted for connection with a source of electric supply, and means by which the fumes or vapors arising from the fusion may be forced through the discharging passage-way, substantially as described.

In witness whereof I have hereunto set my hand this 25th day of April, 1906.

LEON DION.
